WILLIAM S. FRANKLIN, OF SOUTH BETHLEHEM, PENNSYLVANIA.

PUMP.

1,101,266.

Specification of Letters Patent. Patented June 23, 1914.

Application filed January 18, 1913. Serial No. 742,788.

To all whom it may concern:

Be it known that I, WILLIAM S. FRANKLIN, of South Bethlehem, in the county of Northampton, and in the State of Pennsylvania, have invented a certain new and useful Improvement in Pumps, and do hereby declare that the following is a full, clear, and exact description thereof.

The object of the invention has been to provide a pump which, while capable of other uses, shall be specially adapted for use in domestic refrigerating apparatus, and to such ends my invention consists in the pump hereinafter specified.

15 In the accompanying drawing: the figure is a sectional view of a pump embodying my invention.

In the said apparatus is illustrated the best embodiment of the invention known to me, but such embodiment is to be regarded as typical of many possible embodiments, and the invention is not to be restricted to the particular embodiment shown.

20 In the illustrated embodiment, a pump has been provided by which ammonia vapor is condensed and pumped into a condensing pipe, the latter communicating through a suitable valve with a cooling pipe, where the vapor expands for refrigerating purposes and is then returned to the pump.

25 The pump consists essentially of an elastic diaphragm preferably made of sheet steel lying across a shallow lens-shaped cavity between two strong plates and caused to vibrate up and down by alternately pumping a fluid against one side, and allowing the fluid to escape, thus causing the opposite side to admit and compress the vapor to be pumped.

30 In the illustrated embodiment has been provided an elastic diaphragm 1, preferably of sheet steel, which is preferably stretched across a shallow lens-shaped cavity 2 between two heavy plates 3 and 4, respectively. The joints 5 between the said plates are preferably hermetically sealed and the plates are held together as by bolts 6 passing through engaging ears on the plates 3 and 4. The sealing may be accomplished, 35 for example, by autogenous welding.

35 As illustrated, oil is pumped between the plate 4 and the diaphragm 1 to cause the latter to vibrate and such oil enters the cavity between the two through fine 40 perforations 7 in the plate 4, it being delivered

through a pipe 8 by a pump to be described. The pipe 8 preferably carries a collar or washer 9. The joint 10 between such collar and the plate 4 may be sealed by autogenous welding.

45 The said pump consists of a cylinder 11 having a plunger 12 which may be packed by a gland 13 and packing 14. The piston is operated by a rod 15 between which and the piston is interposed a spring 16. In the present instance the piston is provided with a sleeve 17 which incloses the rod 15, but relative movement is permitted by the pin and slot connection 18. The displacement volume of the plunger is made larger than the displacement volume of the diaphragm so that the diaphragm will be pushed against the plate 3 before the plunger reaches the bottom of its stroke, and the continued motion of the pump rod 15 is accommodated by the compression of the spring 16. This spring is under initial compression so that it does not yield until the oil pressure rises above a prescribed volume. An oil reservoir 19 is provided around the 50 pump cylinder and communicates by a check valve 20 with the pump cylinder. During the upstroke of the pump rod the following succession of events take place: (1) The compression spring 12 comes back to its initial position, then the diaphragm moves toward the plate 4 by the back pressure of the ammonia vapor, and then, if there has been any leakage of oil, the continued up movement of the plunger of the oil pump draws in a little oil through the valve 20 from the oil reservoir 19. The region between the diaphragm and the plate 3 is the ammonia pump chamber proper, into which the ammonia vapor enters from the cooling pipe 21, 55 through a valve 22, and from which it is expelled through an outlet valve 23 into the condensing pipe 24. These valves are constructed so as to reduce the clearance space between the diaphragm and the plate 3 to a minimum, and each valve communicates with the region between the diaphragm and the plate 3 through a number of small holes 25 and 26, respectively, thus leaving the face of the plate 3 practically smooth, so

60 that the diaphragm cannot be strained beyond its elastic limit, even though it be made very thin and be forced very strongly against the plate 3.

65 In order to give the valves the smallest 70

possible clearance and make them as simple as possible, I have shown them in the drawings as gravity operated valves, and for this purpose have turned their pipes 21 and 24 vertically, and for simplicity have also made the diaphragm and the plates 3 and 4 vertical. It will be understood, however, that the plates and diaphragm could be made horizontal.

10 It is highly desirable in the operation of the pump that the oil be sure to fall to atmospheric pressure when the oil pump is stopped, and when such action takes place the diaphragm must sustain the full pressure 15 of the ammonia vapor. But the diaphragm must be fairly thin to be operative, and to enable a thin diaphragm to sustain the full pressure of the ammonia vapor, the face of the plate 4 must be practically smooth, so 20 that the diaphragm can fall back flat against it without being strained anywhere beyond its elastic limit. The introduction of the oil through the fine holes 7 meets these conditions. On the other hand, when the diaphragm is forced against the plate 3 to compress the ammonia vapor, as such plate is 25 practically smooth and complete, it perfectly sustains the disk, even though the latter be very thin and be forced completely against 30 the said plate, so as to take up all clearance in the pump. This is because the valves 22 and 23 do not communicate directly with the pump, but only through the fine perforations 25 and 26. Thus the disk is not 35 strained beyond its elastic limit in either direction.

This case is a continuation of my previous application, Serial No. 679,049, filed February 21, 1912, so far as the generic invention 40 is concerned.

I claim—

1. In a pump, the combination with a pumping chamber and an inlet passage and an outlet passage in communication there- 45 with, of a resilient diaphragm secured at its periphery to the inner wall of said chamber so that it lies normally substantially flat, the form of the chamber and the position of the diaphragm being such that the diaphragm 50 may be pressed on its working stroke snugly against the surface of the chamber substantially throughout the extent of both, whereby substantially all clearance within the chamber is avoided, and means for subject- 55 ing the opposite side of the diaphragm to fluid pressure to produce its working stroke.

2. In a pump, the combination with a pumping chamber and an inlet passage and an outlet passage in communication there-

with, of a metallic diaphragm secured at its 60 periphery to the inner wall of said chamber so that it lies normally substantially flat, the form of the chamber and the position of the diaphragm being such that the dia- 65 phragm may be pressed on its working stroke snugly against the surface of the chamber substantially throughout the extent of both, whereby substantially all clearance within the chamber is avoided, and means for subjecting the opposite side of the dia- 70 phragm to fluid pressure to produce its working stroke.

3. In a pump, the combination with a pumping chamber and an inlet passage and an outlet passage in communication there- 75 with, of a metallic diaphragm secured at its periphery to the inner wall of said chamber so that it lies normally substantially flat, the form of the chamber and the position of the diaphragm being such that the dia- 80 phragm may be pressed on its working stroke snugly against the surface of the chamber substantially throughout the extent of both, whereby substantially all clearance within the chamber is avoided, and means 85 for subjecting the opposite side of the dia- phragm to fluid pressure to produce its working stroke, a portion of said apparatus confining the fluid pumped by the said fluid pump being yielding. 90

4. A pump comprising a flexible metal sheet, plates between which said sheet is clamped, said plates being dished so that said sheet may substantially rest against them at the limits of its movement. 95

5. A refrigerant pump comprising a flexible metal sheet, plates between which said sheet is clamped, said plates being dished so that said sheet may substantially rest against them at the limits of its movement, 100 delivery and intake pipes entering through one of said plates, and a fluid pump having a connection through the other of said plates.

6. A pump comprising a flexible dia- 105 phragm, plates between which said dia- phragm is mounted, said plates having lens- shaped cavities therein, which said dia- phragm is adapted to fit at the limits of its movements, a fluid pump and perforations through one of said plates by which said 110 fluid may enter to reach said diaphragm.

In testimony that I claim the foregoing I have hereunto set my hand.

WILLIAM S. FRANKLIN.
